UNITED STATES PATENT OFFICE.

CHARLES HORACE SPOONER, OF CHARLESTOWN, NEW HAMPSHIRE.

JAR-CLOSURE.

1,351,496.

Specification of Letters Patent. Patented Aug. 31, 1920.

Application filed July 9, 1918. Serial No. 244,095.

To all whom it may concern:

Be it known that I, CHARLES H. SPOONER, a citizen of the United States, residing at Charlestown, in the county of Sullivan, State 5 of New Hampshire, have invented a new and useful Jar-Closure; and I do hereby declare the following to be a full, clear, and exact description of the invention, such as will enable others skilled in the art to 10 which it appertains to make and use the same.

This invention relates to an improved jar closure, whereby jars, bottles and the like may be securely sealed when preserving.

15 One of the objects of the invention is to effect the closure of jars and like containers by means of a single piece appliance in conjunction with a flexible sealing ring.

A further object is to insure quick action, 20 in the final closing of the receptacle and quick action in the releasing of the seal when it is desired to open the jar.

A further object of the invention is to make easy the act of and maintenance of 25 sterilization in products best prepared by placing them in the receptacle before cooking.

A further object of the invention is to provide an improved closure, of such character 30 that will facilitate box packing and shelf storing of such receptacles or containers whether filled or emptied.

The first three results or objects may be attained by screw means consisting of sex- 35 tantally interrupted threads, either internally or externally placed about the mouth of the container, the last object by making the top of the closing element essentially flat and of an outside diameter equal to that 40 of the container itself.

A further object of the invention is the provision of means between the contacting parts of the jar and the closure to prevent excessive spreading of the sealing ring.

45 In practical fields the details of construction may necessitate alterations falling within the scope of what is claimed.

The invention comprises further features and combination of parts as hereinafter set 50 forth shown in the drawings and claimed.

In the drawings:—

Figure 1 is a sectional view through the top of a preserving jar or container.

55 Fig. 2 is a sectional view through the closure for the jar in Fig. 1.

Fig. 3 is a plan view of the jar without the closure.

Fig. 4 is an edge elevation of the closure.

Fig. 5 is a sectional view through the upper open end of the jar showing the 60 threaded connections externally arranged.

Fig. 6 is a sectional view through the closure of the jar of Fig. 5.

Fig. 7 is a plan view of the jar of Fig. 5 without its closure. 65

Fig. 8 is an edge view of the closure in Fig. 6.

Referring more especially to the drawings 70 1 designates the mouth end of a jar, the inner wall of which is provided with threads, which are interrupted sextantally.

For instance the threads are divided into sextants, three of which have threads 2, and three others or spaces 3 without threads. In other words the threads are cutaway or 75

interrupted at three intervals, and 4 denotes a suitable closure, comprising a body 5 provided with a circular flange 6. The cylindrical face of the body is provided with threads interrupted sextantally, the sextants 80

of threads 7 adapted to enter the cutaway space 3 of the interior of the mouth end of the jar, so that by imparting a partial turn to the closure said threads 7 may interengage the sextants of threads of the jar. 85

When inserting the closure the sextants of threads 2 will enter the sextants or cutaway spaces 8 of the closure. The marginal edge 90 of the mouth end of the jar is provided with an annular recess 9, the bottom of which is inclined, for the reception of the sealing ring of any suitable material preferably rubber. The bottom of the flange 6 of the closure has an extension 10 the under face

85 of which is inclined to engage the rubber sealing ring (not shown). The inclined faces of the parts 9 and 10 are provided, so 95 as to prevent outward bulge of the sealing ring. The threads 2 and 7 are V-shaped.

In Figs. 5, 6 and 7 the threads 2^a are square 100 or rectangular in cross section, and the sextant spaces 3 are externally arranged on the jar. The threads 7^a and the cutaway spaces or sextants 5^a of the closure 11 are internally arranged. In such structure of

jars and closures the upper marginal edge 105 of the jar in Fig. 7 is inclined as shown at 12, for the reception of the sealing ring of rubber (not shown). The portion 14 of the closure 11 is designed to engage the sealing

110

ring and hold it against the inclined portion 12, and the flange 13 extends into the cavity 15 of the closure 11.

In using this particular device the cover is 5 easily placed in the initial position, with the threads of the closure engaging the sextants or spaces 3, and then by imparting a partial turn to the closure or cover the threads of the cover or closure may quickly 10 mesh with those of the jar mouth, turning the closure or cover one sixth of a revolution to the final seal. Fruits or vegetables requiring to be placed in the jars cold, the cover may be at once placed in the initial position 15 and allowed to so remain until sterilization is completed and then quickly turned to final position, thereby preventing air or any deleterious element from entering.

The invention having been set forth what 20 is claimed as new and useful is:—

The combination with a jar having a mouth end provided with interior interrupted threads, of a closure comprising a body fitting into the mouth end and provided with interrupted threads to engage the 25 threads of the interior of the mouth end, the

marginal edge of the mouth end having an annular recess, said annular recess inclining inwardly and downwardly and having its inner wall substantially vertical, the body 30 of the closure having an annular flange, said annular flange on its under face being provided with an annular recess, which annular recess inclines inwardly and upwardly, an annular recess concentric with the recess of 35 the under face of the flange and adjacent thereto, said second annular recess of the flange and the inclined recesses of the flange and marginal edge of the jar mouth forming means for clamping a rubber washer 40 in such a manner so that the same will be held against outward spreading by the annular recesses which incline inwardly and downwardly and inwardly and upwardly.

In testimony whereof I have signed my 45 name to this specification in the presence of two subscribing witnesses.

CHARLES HORACE SPOONER.
